UNITED STATES PATENT OFFICE.

CHARLES L. HUTCHINGSON, OF BROOKLYN, NEW YORK, ASSIGNOR TO CAMERON MACHINE COMPANY, OF BROOKLYN, NEW YORK, A CORPORATION OF NEW YORK.

MACHINE FOR THE SIMULTANEOUS SLITTING AND ARTIFICIAL SELVAGING OF FABRICS.

1,368,933.

Specification of Letters Patent. Patented Feb. 15, 1921.

Application filed August 7, 1918. Serial No. 248,723.

To all whom it may concern:

Be it known that I, CHARLES L. HUTCHINGSON, a citizen of the United States, and a resident of the borough of Brooklyn, in the city of New York, county of Kings, and State of New York, have invented certain new and useful Improvements in Machines for the Simultaneous Slitting and Artificial Selvaging of Fabrics, of which the following is a specification.

The present invention relates generally to machines for producing artificial selvage on fabrics while they are being slit and has more particularly reference to devices for combining the slitting operation with that of applying a stiffening compound or paste to the edges of the slit material.

The main object of the invention is to associate paste-applying means with slitting means in such a way that the requisite degree of pressure for effectual severance of the web may be exerted upon the slitting members; and, at the same time, to afford adjustability of, and accessibility to, the parts.

The invention consists of the hereinafter described features of construction, arrangement of elements and combination of parts.

In the accompanying drawings, the invention is shown in a concrete and preferred embodiment in which—

Figure 1 is a sectional view of part of a slitting and rewinding machine to which the invention has been applied.

Fig. 2 is a sectional view on the line 2—2 of Fig. 1.

1 indicates a rewinding shaft on which the material 2 can be rewound after it has been slit, the rewinding operation being preferably performed by surface rewinding rolls 3 and 4 and by a top rewinding roller 5. In the form here disclosed, a rewinding roller 4 constitutes one of the slitting elements in that it acts as a backing roller for a plurality of cutting members, such as the score cutters 6. The material is fed to the device in any suitable manner, such for instance, as over a guide bar 7 between the backing roller 4 and score cutters 6, and thence to a rewinding shaft 1. The score cutters 6 are each mounted in a bifurcated extension 8 of a rocking bar or member 9 pivotally mounted on a transverse member 10, the

other end of which is provided with springs 11 that bear upon an abutment 12, as shown. 55 The transverse member 10 rests on an eccentric 13 mounted in adjustable bearings in a manner known so that by turning said eccentric, score cutters 6 will be moved toward and away from backing roller 4. It 60 will be understood that eccentric 13 may be turned, even after the score cutters 6 have come into engagement with the member 4 since continued movement of eccentric 13 merely places upon spring 11 a greater 65 tension. It will thus be seen that each score cutter 6 is individually articulated and spring-pressed with relation to backing roller 4; and that should there be any discrepancy in the diameter of score cutters 6, 70 eccentric 13 may be moved until that score cutter having the smallest diameter is in engagement with the backing roller 4. To prevent the formation of grooves in it by score cutters 6 the backing roller 4 is provided with a sleeve 14 of material harder 75 than that of the score cutters.

For each cutter there is provided a paste-applying roller 15 that may be made of fibrous or other material. These paste-applying rollers are individually articulated, and also, in a manner to be described, individually spring-pressed; and rotate in the fountain or bath in engagement with the edge of the score cutter 6. They are so 85 mounted as to partake of the movement of the supporting member 9 when it is adjusted under the influence of eccentric 13.

At the underside of each supporting member 9 is a bearing 17 in which is pivoted, 90 at 19, an arm 18 that supports the paste-applying roller 15. An expansion spring 20 bears, at one end, against bracket 17 and, at its other end, against arm 18 of lever 18 and thus maintains the paste-applying roller 95 in engagement with score cutter 6.

21 indicates a scraper, conveniently mounted, by means such as screw 22, on the upper side of rocking member 9, that engages the surface of the paste-applying roller 15 and 100 extends down between the ends of the bifurcated extension 8, as shown. The tension of this scraper may be suitably adjusted by means of screw 23. It will be observed that when eccentric 13 is adjusted, score cutters 6 and paste-applying wheels 15 will be

elevated as a group, until proper contact has been made between the score cutters and the backing roller 4; and that the tension of paste-applying rollers 15 against score 5 cutters 6 individually will be unaffected whatever may be the position of the rocking member 9 and the tension of spring 11 against said rocking member. As the material is fed between backing roller 4 and 10 score cutters 6, it is divided or slit into a number of sections; and, at the same time, a stiffening compound or paste is applied, by means of score cutters 6, on both sides of the slit made in the material. The application 15 of this stiffening compound has the effect of producing what may be termed an artificial selvage on the slit sections and the sections may then be rewound in the manner described.

20 I claim:

1. A machine for producing artificial selvage on fabrics while being slit comprising: a backing roller, a plurality of cutters engaging said backing roller, an individual 25 spring-pressed rocking support for each cutter, an individually articulated paste-applying roller carried by each support beneath the cutter and engaging with the cutter of that support, and means for supplying paste 30 to the paste-applying rollers.

2. A machine for producing artificial selvage on fabrics while being slit comprising: a backing roller, a plurality of cutters engaging said backing roller, an individual 35 spring-pressed rocking support for each cutter, an individually articulated paste-applying roller carried by each support beneath the cutter and engaging with the cutter of that support, means for supplying paste to 40 the paste-applying rollers, and means for raising and lowering the rocking supports as a group with respect to the backing roller.

3. A machine for producing artificial selvage on fabrics while being slit comprising: a backing roller, a plurality of cutters engaging said backing roller, an individual 45 spring-pressed rocking support for each cutter, an individually articulated paste-applying roller carried by each support beneath the cutter and engaging with the cutter of that support, means for supplying paste to the paste-applying rollers, and a scraper carried by each support engaging with the paste-applying roller of that support.

50 4. A machine for producing artificial selvage on fabrics while being slit comprising; a backing roller, a plurality of cutters engaging said backing roller, an individual 55 spring-pressed rocking support for each cutter, an individually articulated paste-applying roller carried by each support beneath the cutter and engaging with the cutter of that support, means for supplying paste to 60 the paste-applying roller of that support.

the paste-applying roller, a scraper carried by each support engaging with the paste- 65 applying roller of that support, and means for raising and lowering the rocking supports as a group with respect to the backing roller.

5. A machine for producing artificial selvage on fabrics while being slit comprising: a backing roller, a plurality of cutters engaging said backing roller, an individually 70 spring-pressed rocking support for each cutter terminating in a forked extension that carries the cutter, an individually articulated paste-applying roller carried by each support and engaging with its cutter at the underside thereof, a scraper carried on the upper side of each support and projecting through the bifurcated extension 75 into engagement with the paste-applying roller of that support, and means for supplying paste to the paste-applying rollers.

6. A machine for producing artificial selvage on fabrics while being slit comprising: a backing roller, a plurality of cutters, engaging said backing roller, an individually 80 spring-pressed rocking support for each cutter terminating in a forked extension that carries the cutter, an individually articulated paste-applying roller carried by each support and engaging with its cutter at the underside thereof, a scraper carried on the upper side of each support and projecting through the bifurcated extension 85 into engagement with the paste-applying roller of that support, means for supplying paste to the paste-applying rollers, and means at the upper side of each support for 90 adjusting the tension of the scraper carried by that support.

7. A machine for producing artificial selvage on fabrics while being slit comprising: a backing roller, a rocking support, a 105 cutter carried by said support and engaging with the backing roller, a paste-applying roller carried by the rocking support beneath the cutter, and means for supplying paste to the paste applying roller.

8. In a fabric slitting machine an arm, a rotary cutter pivotally carried thereby, a roll movably carried by said arm for peripheral contact with said cutter, and means to retain said cutter and roll in engagement.

9. In a fabric slitting machine an arm, a rotary cutter pivotally carried thereby, a roll movably carried by said arm for peripheral contact with said cutter, and a spring operatively connecting said roll with said 120 arm to resiliently retain them in peripheral engagement.

Signed at Brooklyn, in the county of Kings and State of New York, this 2 day of August, 1918.

CHARLES L. HUTCHINGSON.
